CLAIM

The ornamental design for a protective hang cover skin for electronic device, as shown and described.

DESCRIPTION

FIG. 1 is a front, top and right perspective view of protective hang cover skin for electronic device showing claimed design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a rear, bottom and right perspective view thereof;

FIG. 9 is a cross-sectional view taken along line 9-9 shown in FIG. 2; and,

FIG. 10 is a front, top and right perspective view thereof with a top portion open in use.

The broken lines shown in FIG. 10 depict environment and form no part of the claimed design.
